UNITED STATES PATENT OFFICE.

CHARLES W. BOOTH, OF CHICAGO, ILLINOIS.

GOLF CLUB.

1,412,650.

Specification of Letters Patent. Patented Apr. 11, 1922.

Application filed March 6, 1919, Serial No. 280,974. Renewed November 13, 1921. Serial No. 516,250.

To all whom it may concern:

Be it known that I, CHARLES W. Booth, a citizen of the United States, and a resident of Chicago, in the county of Cook and State 5 of Illinois, have invented a certain new and useful Improvement in Golf Clubs, of which the following is a specification.

This invention relates to golf clubs and relates particularly to drivers and brassies 10 having metal plates inserted in their driving faces and weights in their rear sides.

In clubs having metal plates in their driving faces, it is very important that the metal plates shall be drawn into very close, firm 15 and strong contact with the bearing faces therefor on the body portions of the clubs, as, otherwise, the impact of the club in striking a ball is "deadened" and the "drive" very materially shortened.

20 To effect the foregoing object, I connect the face plate of the club with the weight and provide opposed bearing surfaces on the body portion of the club for said face plate and weight, so disposed with relation to each 25 other, that when said face plate and weight are applied to the club they will exert a wedging action which will operate to draw both said face plate and weight into very close, firm bearing with the surfaces on the 30 head of the club with which they are designed to contact, respectively, in which positions they are secured by suitable means.

A further object of the invention is to provide a construction in a club of the type 35 specified adapted for use both in "drivers" and "brassies." To this end, I provide a metal guard plate formed integral with the face plate of the club corresponding to the usual fibre guard plates secured to the front 40 edges of the soles of drivers, which will serve to protect the edge of the driver and will also answer the purpose of the sole plate used on "brassies."

The invention also comprises the various 45 other features and details of construction hereinafter described and claimed.

In the accompanying drawings, in which my invention is fully illustrated,

Figure 1 is a face view of a club head embodying my invention.

Figure 2 is a rear view thereof.

Figure 3 is a bottom plan view thereof.

Figure 4 is a sectional view thereof taken on the line 4-4 of Fig. 1.

55 Referring now to the drawings, 1 designates the head of a "driver," "brassy" or

other wooden club, which may be of any usual or approved construction.

Secured to the club head 1 is what, for purposes of convenient reference, I shall designate a "fitting," comprising a face plate 2 secured in the driving face of the club head, a weight 3 secured to the rear side of the club head, a bar 4 which connects said face plate 2 and weight 3 and a guard plate 5 secured to the front edge of the sole of the club. Said fitting is made of brass or other suitable metal, the parts thereof being preferably formed integral with each other. In practice, said fitting may conveniently be formed by casting.

In the preferable construction shown, all of the component parts of said fitting are mortised into the body portion of the club head 1 so that the outer surfaces thereof will 75 be substantially continuous with the surfaces of said club head into which they are inset, respectively, and are so proportioned that the center of gravity of the club head will 80 be substantially in line with the shaft of the club.

As shown, the bar 4 is connected to the lower edges of the face plate 2 and of the weight 3, the mortises for both said face plate and weight "cutting out" at the bottom edges 85 of said club head and the lateral edges of said face plate and of the mortise therefor in the club head converge slightly and correspondingly from the edge of said face plate to which said bar 4 is connected towards 90 their opposite sides or edges, thus providing for slipping said fitting into position on said club head from the under side.

A particular advantage of my improved club is that all of the mortises or cut-out 95 portions of the club head which are to receive the fitting to be applied to the club head may be routed out by machinery in a simple and inexpensive manner.

To provide for drawing the face plate 2 and weight 3 into desired close contact with the surfaces on the club head with which they are designed to contact, respectively, the bearing surfaces for and of said face plate and weight preferably diverge upwardly—that is, away from the sole of the club head or from the bar 4—relatively to each other, thus forming wedging surfaces, and the distance between the bearing surfaces on said face plate and weight is so 110 slightly less than the distance between the corresponding bearing surfaces on the club

head, that when said fitting is fully seated on the club head, a wedging action will be exerted on said face plate and weight, which will operate, in an obvious manner, to draw 5 said face plate and weight into very close, strong bearing against the bearing surfaces on the club head.

When the fitting has been adjusted to the club head in the manner described, it is 10 then rigidly connected thereto by suitable means, as screws inserted through said face plate and weight, the screw inserted through said weight preferably being inserted in such manner that it will tend to draw the 15 bearing surface thereon into wedging engagement with its bearing surface on the club head.

A simple method of securing a desired 20 tight fit between the opposed bearing surfaces on said face plate and weight and on the club head, is to make the angle of divergence between the bearing faces on said face plate and weight slightly less than the angle of divergence between the bearing 25 surfaces thereon on the club head and in making the bar 4 sufficiently stiff and strong so that, when said fitting is forced into place on said club head, the rigidity of said bar will resist the spreading action exerted on 30 said face plate and weight by the bearing surfaces on the body portion of the club head—due to the greater divergence of said bearing surfaces on the club head—causing said face plate and weight to grip the bearing 35 surfaces on said club head with a strength of engagement corresponding to the rigidity of the bar 4.

I claim:—

1. In combination with a wood golf-club 40 head, an integral metal fitting therefor embodying a weight set in the back wall of the club and having its lower edge forming a part of the bottom face of the club, a bar extending fore and aft of the club and set 45 in the bottom face of the club flush with the adjacent wood bottom surface of the club, and a plate connected to the forward end of the bar and set in the bottom face of the club flush therewith, said plate extending 50 across the front edge of the club and

having an upwardly-extending plate set in the front, striking, face of the club flush therewith.

2. A golf club comprising a head or body portion and a fitting secured thereto, said fitting comprising a face plate secured in the face of the club head, a weight secured to the back of the club head and a bar which connects the lower edges of said face plate and weight, the bearing surfaces on said face plate and weight and the surfaces on the club head with which they contact, respectively, diverging away from the sole of the club head, the relation being such that when said fitting is adjusted to said club 65 head, the contacting surfaces on said face plate and weight and the surfaces on said club head opposed thereto will exert a wedging action which will draw said face plate and weight into strong engagement with 70 their bearing surfaces on the club head, substantially as described.

3. A golf club comprising a head or body portion and a fitting secured thereto, said fitting comprising a face plate secured in 75 the face of the club head, a weight secured to the back of the club head and a bar which connects the lower edges of said face plate and weight, the bearing surfaces on said face plate and weight and the surfaces on the club head with which they contact, respectively, diverging away from the sole of the club head, the relation being such that when said fitting is adjusted to said club 80 head, the contacting surfaces on said face plate and weight and the surfaces on said club head opposed thereto will exert a wedging action which will draw said face plate and weight into strong engagement with 85 their bearing surfaces on the club head, the divergence of the bearing surfaces on said face plate and weight being initially slightly less than the divergence of the bearing surfaces thereon, respectively, on the club head, substantially as described. 90

In testimony that I claim the foregoing as my invention, I affix my signature this 95 3rd day of March, 1919.

CHARLES W. BOOTH.
